CLAIM

The ornamental design for a display screen with graphical user interface, as shown and described.

DESCRIPTION

The single FIGURE is a front view of the display screen with graphical user interface showing the new design. The dot-dash line showing of the display screen is for the purpose of illustrating portions of the article and forms no part of the claimed design. The broken line showing of text and other portions of the graphical user interface is for the purpose of illustrating portions of the article and forms no part of the claimed design.
